CLAIM

The ornamental design for a combined storage and dispensing container for sand or the like, substantially as shown and described.

DESCRIPTION

FIG. 1 is a perspective view of a combined storage and dispensing container for sand or the like showing my new design;

FIG. 2 is a rear elevational view thereof;

FIG. 3 is a front elevational view;

FIG. 4 is a bottom plan view thereof; and

FIG. 5 is a top plan view thereof.
